UNITED STATES PATENT OFFICE.

JOHN M. RUSBY, OF PHILADELPHIA, PENNSYLVANIA, ASSIGNOR TO THE UNITED GAS IMPROVEMENT COMPANY, OF PHILADELPHIA, PENNSYLVANIA, A CORPORATION OF PENNSYLVANIA.

HEATING COAL-GAS-RETORT CHAMBERS AND THE LIKE.

1,140,337.

Specification of Letters Patent. Patented May 18, 1915.

Application filed June 27, 1914. Serial No. 847,566.

To all whom it may concern:

Be it known that I, JOHN M. RUSBY, a citizen of the United States, and a resident of Philadelphia, in the county of Philadelphia and State of Pennsylvania, have invented certain new and useful Improvements in Heating Coal-Gas-Retort Chambers and the like, of which the following is a specification.

- 10 In the operation of coal gas apparatus it has always been necessary to employ some device for controlling the temperature of the solid fuel burning producers which serve for the heating of this apparatus; this temperature control is necessary because of the presence of ash in this solid fuel, and because of the tendency of this ash to fuse, at high temperature, and aggravate into masses of clinker, which cause serious trouble; also, 15 temperature control is necessary in order to avoid injury to the brick, or other refractory material, of which the producer is constructed.
- 10 It has long been common art to pass steam through the producer fuel bed for the purpose of lowering the temperature of the fuel bed, and thus avoiding the foregoing high temperature troubles; this steam in its passage through the fuel bed is wholly, or 20 in part, decomposed into its chemical constituents with simultaneous absorption of heat from the fuel bed; steam is a very suitable material to use for this cooling of the fire, since the volume that is required to 25 effect a given temperature reduction in the fire is comparatively small in respect to other agents that have been used or suggested for that purpose, and this steam can be easily supplied and passed through the 30 fire. Furthermore, however, the types of apparatus which has been recently introduced for coal gas manufacture are of such large size, and subjected to such heavy pressures of weight of material, that the existence 35 of high temperatures is more dangerous to the structural material than formerly, and it is now found necessary to obtain a control of the temperatures not only in the producer fuel bed, but also in the retort 40 chambers in which is consumed, for heating, the gas which is generated in the producers. Now it can be shown by accurate calculation that the steam which, as in the foregoing, has heretofore been used for the 45 control of the producer fuel bed temperature 50 also has an effect in lowering the temperature yielded by final combustion of the producer gas in the retort chamber; consequently a sufficient lowering of the temperature in the retort chamber could be 55 attained by the passage of a sufficiently large quantity of steam through the producer bed. The following important facts, however, are to be observed. Steam is, of course, expensive, requiring the cost of fuel 60 for its evaporation, and whatever steam is used is finally discharged to the atmosphere at the stack and wasted, thus causing a loss of this heat required for its evaporation, and also whatever sensible heat it contains above 65 this temperature of evaporation. Also, it is desirable, in order to obtain the best quality of producer gas and the most thorough utilization of the steam supplied, to not reduce the temperature of the producer fuel 70 bed below the point which will insure freedom from clinker and prevention of destruction of the refractory material of the furnace. In respect to the tendency to form clinker, and consequently the temperature 75 required, different fuels will vary very greatly, as will also the ability of the materials of which the producer is constructed, to withstand high temperature; for instance, with a fuel approximating to pure carbon, 80 and with the best grade of material employed in the construction of the producer, both the fuel bed and the structural material would endure the maximum temperature 85 attainable in combustion and consequently no cooling of the fire, and no steam supply thereto, would be required, whereas under different fuel and structural material 90 conditions, the required cooling of the fuel bed, and steam supply, will be great; it is an important fact, however, that such variation in degree of cooling of the producer fuel bed will, unless combined supplementary method of control be provided, produce corresponding and injurious or dangerous variations in temperature of the retort chamber and other parts of the apparatus, and to prevent such injurious temperature 95 variations, such supplementary control must be provided.
- 10 I have discovered that the quantity of steam supplied through the producer fuel bed can be appropriate for the fuel em-

ployed and the character of the structural material of the producer and need not exceed that quantity, and that the use of steam should be combined with a cheaper and more satisfactory method to separately and simultaneously control the temperature of the retort chamber to any extent whatever which may be required.

The principal object of the present invention is therefore to more economically, more efficiently and separately or independently control the temperature of the fire so as to avoid the formation of clinkers and injury to the producer, and the temperature of the retort chamber so as to avoid undue local or excessive heating of the structural materials and to effect therein a uniform distribution of heat or regulation or control of temperature effect of secondary combustion or retort heating.

To this and other ends hereinafter set forth the invention comprises the process of heating coal gas retort or coal carbonizing chambers which consists in generating producer gas from fuel with air, burning the producer gas with secondary air in the retort chamber and separately controlling the fire and chamber temperatures by passing sufficient steam through the fire to keep its temperature below that which will cause the formation of clinkers or injure the producer and by adding to the combustion of the producer gas an appropriate incombustible diluent, whereby only so much steam is passed through the fire as is required for the avoidance of clinkers, and whereby little or no power is required for the introduction of the incombustible diluent which may be products of combustion, while at the same time the bench is operated economically, efficiently and uniformly.

An apparatus in connection with which the process of the invention can be practised has been chosen from among other apparatus capable of the same use and illustrated principally in section in the accompanying drawings.

In the drawings 1 is the coal gas retort chamber and 2 is a grate or the like upon which a burning fuel bed or fire is supported or maintained. Producer gas is generated in the producer 3 by the passage of air through the fire or burning fuel bed.

4, is a metering device for introducing primary air beneath the grate 2.

5, is a means for introducing secondary air into the retort chamber 1. It is shown as connected with the recuperator 6, so that producer gas rising from the producer 3 meets the secondary air at 5 and is burned, the products of combustion passing through the retort chamber to 7, and then traversing the recuperator 6, finally reaching the stack 8.

65. 9, is a steam meter having a regulatable

connection for passing steam beneath the grate and through the fire or burning fuel bed. Incombustible products of combustion may be taken from the exit of the retort chamber and added to the burning products 70 of combustion of the producer gas by way of the passage 10 and metering device 11, or incombustible products of combustion may be taken after they leave the recuperator and are on their way to the stack by way of 75 the passage 12 of the metering device 11. The position of the slide valve 13 determines from which source the incombustible products of combustion are taken for supplying the opening of the metering device 11. The 80 slide valve 13 may be positioned as desired by means of a rod that can be introduced through the stoppered opening 14. 11², is a guage which completes the metering device 11. A jet of steam, or the like, 15 may be 85 used in connection with the metering device 11 for delivering the incombustible products of combustion.

In the practice of the invention and for all practical purposes, the control of the 90 retort chamber temperature and of the fire temperature are independent. Inasmuch as the incombustible diluent is added to the combustion of the producer gas, it follows that the diluent does not pass through the 95 fire, which is advantageous because the resistance of the fuel bed is considerable and it would require power to force the incombustible diluent through it. Furthermore, steam being under pressure can be inexpensively put through the fire because its pressure, which is cheaply attained, is sufficient to overcome the resistance of the fuel bed. Moreover only the steam necessary to avoid 100 clinkers, or undue heating of the producer, may be used and the rest of the temperature control effected by means of the incombustible diluent, which may be products of combustion obtainable without cost and cheaply applied when introduced in the manner described at a point where they do not have to be forced past the resistance of the fuel bed. Furthermore any steam decomposed in the 105 fire returns to steam when it meets the secondary air, so that all steam introduced is 110 eventually lost up the stack, whereas products of combustion returned above the fire, as described, are continually circulated and returned and no heat is lost.

By way of further explanation it may be 120 said that with some fuels, the amount of steam required to avoid clinker would be insufficient for preventing damage to the brick-work by the secondary combustion and in such case it is evident that an economy 125 is effected by using only the amount of steam necessary for preventing clinker and supplementing it with incombustible products of combustion introduced to the burning products of producer gas in order to 130

regulate and control the temperature effects of the secondary combustion in respect to the safety of the brick-work of the retort chamber and of the retorts. The volume of steam practically required to be passed through a fire of fuel of ordinarily good quality to avoid clinker is about thirty-one cubic feet per pound of carbon consumed and its weight is about one and one-quarter pounds. Contrasted with this the volume of combustion products that would have to be passed through a like fire for the same purpose is seventy-eight cubic feet per pound of carbon consumed and its weight would be over six pounds.

Evidently if the steam through the fire were relied upon for both the fire and retort temperature control, the quantity of it required for the fire control might be wholly inappropriate for the retort temperature control. Furthermore while it is desirable to use steam through the fire because it can, by reason of its pressure, be cheaply put through the fire, it is undesirable to use steam for the retort chamber control because all steam used is finally wasted by going up the stack. While products of combustion cost nothing and are easily introduced to the burning producer gas, still it is expensive by reason of their great weight and volume to force them through the fire or fuel bed; whereas their introduction into the burning producer gas is not only easy but efficient and not wasteful of heat. At some times the quality of fuel may be so good that no steam or other cooling agent is necessary in order to avoid clinker, and in such cases the independent regulation of the retort chamber temperature is particularly advantageous.

By the described process the advantages of each plan are attained and the disadvantages of each is avoided and the combination of the two gives an efficient, economical and easy control of the temperatures throughout the setting, including the temperature of the fire, such as has not heretofore been attained.

What I claim is:

1. The process of heating coal carbonizing chambers which consists in generating producer gas from a fire with air, burning the producer gas with secondary air to heat said chamber and separately controlling the fire and chamber temperatures by passing sufficient steam through the fire to keep its temperature below that required for the formation of clinker or for injury to structural material and by adding to the burning producer gas a diluent consisting of incombustible products of combustion, substantially as described.

2. The process of heating coal carbonizing chambers which consists in generating producer gas from a fire with air, burning the producer gas with secondary air to heat said chamber and separately controlling the fire and chamber temperatures by passing sufficient steam through the fire to keep its temperature below that required for the formation of clinker or for injury to structural material and by adding to the combustion of producer gas an incombustible diluent, substantially as described.

In testimony whereof I have hereunto signed my name.

JOHN M. RUSBY.
